D. R. COOPER.
INHALING APPARATUS.
FILED MAY 4, 1920.

Invantor-
Daniel Richard Cooper
By - B. Smigel, Atty.

Patented Jan. 16, 1923.

UNITED STATES PATENT OFFICE.

DANIEL RICHARD COOPER, OF GORE, NEW ZEALAND, ASSIGNOR TO CHARLES WILLIAM ANDERSON AND FLORENCE LOUISA HOWORTH, BOTH OF WELLINGTON, NEW ZEALAND.

INHALING APPARATUS.

Application filed May 4, 1920. Serial No. 378,925.

To all whom it may concern:

Be it known that I, DANIEL RICHARD COOPER, a subject of the King of Great Britain and Ireland, residing in Gore, in 5 the Dominion of New Zealand, have invented a new and useful Improvement in Inhaling Apparatus; and I do hereby declare the following to be a full, clear, and exact description of the same.

10 This invention relates to that class of apparatus employed for inhaling medicines of a vapourizing nature, and more particularly useful in connection with medicines that are used by the inhalation system for the treatment of nasal, throat and chest complaints 15 and diseases.

The object of the invention is to permit of the vapours from medicines of a volatile nature being easily regulated, and any suitable combinations of the vapours from such 20 medicines inhaled with any desired admixture of air, either through the nasal passages or by means of the mouth.

The invention will be fully described with 25 the aid of the accompanying drawings, in which:—

Figure 1, is a sectional side elevation.

Figure 2, is a similar view showing a combined mouth and nose piece.

30 Figure 3, is a side elevation partly in section showing a form having air regulating means thereon.

Figure 4, is a plan in which a double nose piece is employed.

35 Referring to the drawings, the inhaler consists of a casing 1 made of suitable material and having an air or vapour passage 2 extending longitudinally through the lower portion of the casing 1. Chambers 3

40 are arranged in the casing 1, each of which opens out through the top of the casing 1 and is furnished with a stopper 4 having a passage 5 into which a plug 6 fits. Any desired number of these chambers may be 45 employed, the drawings showing three.

The bottom end of each chamber communicates with the air passage 2 by an orifice 7, so that when anyone of the plugs 6 is removed, a passage for air is formed through 50 the corresponding chamber 3 into the air passage 2. The ends of the air passage 2 are respectively provided with a removable nose piece 8 and mouth piece 9. These respective nose and mouth pieces are shaped

as shown for entering the nostrils and 55 mouth of the user and have passages 10 adapted to be closed by plugs 11 fitted therein in order that either may be closed at will. If desired, the mouth and nose pieces may be made in one as shown in Figure 2, 60 so that by reversing this unit it may be employed for either purpose. By this arrangement the mouth and nose piece, after being used is reversed and the end which is inserted 65 into the air chamber is sterilized by means of the vapours within the air passage. The chambers 3 are adapted to receive and hold a quantity of cotton wool or other absorbent, which is saturated with the desired volatile medicine and this wool is preferably 70 retained in a holder whereby it may be easily inserted and removed.

A suitable holder is shown in the figures and consists of a helical wire cage 12 fitting loosely into the respective chambers 3. Such 75 form of holder ensures that the air currents will not be blocked, and at the same time provides that such currents will come into intimate contact with the saturated absorbent and thereby take up the maximum quantity 80 of the medicine vapour.

In use, when the vapours from one medicine chamber only is required, the plug 6 from the stopper is removed, but the plugs from the stoppers of the other chambers are 85 left in position and the air is drawn through the one chamber vapourizing the medicine and carrying the vapour to the nose or mouth.

If the air is desired to be drawn through 90 two or more chambers, the respective plugs of these chambers are removed and the air drawn through them. If desired, and in order to permit the air current to pass equally through each absorbent the holders 12 may 95 be removed from the chambers and placed in the air passages 2 as shown in Figure 1 and an air current induced through one chamber and through the holders and absorbent material placed in the air passages. 100

In Figure 3, the chambers 3 are made with circular tubes to receive caps 14 having air inlet orifices 15 corresponding to air inlet orifices 16 in the wall of the chambers. By these means the air may be regulated to each chamber. In Figure 4, a nose piece is employed having branches 17 and 105 18 for insertion into each nostril.

What I claim is:—

1. Inhaling apparatus comprising a casing, an air passage extending longitudinally through the casing, a nose piece fitted into said passage at one end thereof, a mouth piece fitted into said passage at the other end thereof, chambers in said casing to receive absorbent material adapted to be saturated with the required medicine, a passage from each of said chambers to the said air passage and means for admitting air to the said chambers and for closing the ends of the said chambers from air, said mouth or nose piece removable from said passage, substantially as described.
2. Inhaling apparatus comprising a casing, an air passage extending longitudinally through the casing, a nose piece fitted into said passage at one end thereof, a mouth piece fitted into said passage at the other end thereof, chambers in said casing to receive absorbent material adapted to be saturated with the required medicine, a passage from each of said chambers to the said air passage and means for admitting air to the said chambers and for closing the ends of the said chambers from air, and a holder within said chambers for containing absorbent material, substantially as described.
3. Inhaling apparatus comprising a casing, an air passage extending longitudinally through said casing, a removable nose and mouth piece fitted into said passage, said

passage adapted to contain absorbent material adapted to be saturated with the required medicine, chambers above said passage of a diameter corresponding with that of the air passage to receive absorbent material, a passage from each of said chambers to the said air passage and the upper portion of each chamber having closure means so that air may be drawn through one or more of such chambers, said nose and mouth piece made in one piece and reversible in said casing, substantially as described.

4. Inhaling apparatus comprising a casing, an air passage extending longitudinally through said casing, inhaling means fitted into said passage, chambers in said casing to receive absorbent material adapted to be saturated with the required medicine, a passage from each of said chambers to the said air passage, caps screwing upon the tops of said chambers, air orifices in said caps and in the walls of said chambers whereby the air supply to the said chambers may be regulated, substantially as described.

In testimony whereof, I have signed my name to this specification in the presence of two subscribing witnesses.

DANIEL RICHARD COOPER.
